UNITED STATES PATENT OFFICE.

WILLIAM F. MARTIN, OF WORMLEYSBURG, PENNSYLVANIA.

COAL WASHER AND SEPARATOR.

1,412,291.

Specification of Letters Patent. Patented Apr. 11, 1922.

Application filed September 12, 1921. Serial No. 500,101.

To all whom it may concern:

Be it known that I, WILLIAM F. MARTIN, a citizen of the United States, residing at Wormleysburg, in the county of Cumber-

5 land and State of Pennsylvania, have invented certain new and useful Improvements in Coal Washers and Separators; and I do declare the following to be a full, clear, and exact description of the invention, such as

10 will enable others skilled in the art to which it appertains to make and use the same.

This invention relates to an improved device for washing and separating coal, ore, and the like.

15 The principal object of the invention is to generally improve upon devices of this class by the provision of one of extreme simplicity and durability which embodies a trough having a screen onto which the material to

20 be washed and separated is deposited, together with a number of pockets underneath of the screen for collecting the waste materials which are separated from the usable or desired materials by the water which passes

25 downwardly through the trough and into and out of the various pockets.

Another object of the invention is to provide a device of the class described embodying the aforesaid structure the pockets including retractile side portions for permitting the contents thereof to be disposed of whenever desired.

A further object of the invention is to provide a device of this class wherein the 35 aforesaid pockets are relatively shallow and are disposed very close to one another so that the current of water will rise to a sufficient height before passing through the discharge opening to contact any waste material which tends to stay on the screen, thus loosening and carrying said material with it through the discharge.

A still further object of the invention is to provide a device of this class including novel 45 means for simultaneously actuating the retractile portions of the various pockets, said means being located at points where it can be operated conveniently from either end of the trough.

50 Other objects and advantages of the invention will be apparent during the course of the following description.

In the accompanying drawings forming a part of this specification and in which like numerals are employed to designate like parts throughout the same:

Figure 1 is a top plan view of a device constructed in accordance with this invention, a portion of the separating screen being broken away to disclose the details beneath it more clearly.

Figure 2 is a side elevational view of the device.

Figure 3 is a bottom plan view thereof showing the movable sides of the pockets open.

Figures 4 and 5 are central longitudinal sectional views through the trough showing the movable sides of the pocket open and closed respectively.

Figure 6 is a transverse sectional view taken substantially on the plane of the line 6-6 of Fig. 5.

Referring to the drawings in detail, it will be seen that the numeral 1 designates generally an elongated trough which is de-

signed to be supported in downwardly inclined position by any suitable means. This trough is preferably made up of spaced parallel side pieces 2 connected together at their ends by cross-pieces 3. Secured to the parts

2 and 3 adjacent the upper edges of the latter and stretched across and held in place in any suitable manner is a suitable straining device in the form of a fine mesh screen 4.

At this point it may be stated that the cross-piece at the lower end of the trough is not quite as high as the one at the opposite end so as to permit the coal or other material being acted on to be easily discharged from the trough.

As previously indicated, beneath this screen 4 is a plurality of closely disposed adjoining pockets 5 so constructed as to permit the contents thereof to be easily and readily removed whenever desired or necessary and although the pockets may be constructed in various ways to accomplish this end, I prefer to form each one from a relatively wide downwardly inclined board 6 rigidly secured to the side pieces 2, together with a relatively narrow substantially vertically disposed board 7 which is hingedly connected to an adjacent board 6 and bears against the lower longitudinal edge of the

board with which it cooperates to provide a pocket.

To hold the boards 6 and 7 in operative or closed position such as shown in Fig. 4, 5 I prefer to make use of novel means which is such that it simultaneously moves all of said boards to the position shown in Fig. 5 to enable the contents thereof to be disposed of. While this means may be of other construction, 10 I prefer to simply employ a relatively long rod 8 which extends entirely beneath the various pockets, the same being pivotally connected at the points 9 with depending brackets 10 rigidly secured to the intermediate portions of the boards 7. It is obvious 15 that by moving this rod longitudinally in one direction or the other, the board 7 will be moved with it and will assume either of the positions shown in Figs. 4 or 5 according to the direction of movement of the rod. In order to impart such movement to the latter, I make use of novel means which serves to hold it in a set position and serves to permit it to be operated from either end of the trough. 20 This means preferably consists of links 11 which are pivotally connected to one end of the rod and to a crank arm 12 on a cross shaft 13 rotatably mounted in suitable bearings carried by the longitudinal side pieces 2. The rod 13 extends beyond one of said side pieces and an operating lever 14 is fixed thereto for the purpose of rotating the rod as is obvious. It is desired to associate 25 with this lever, a suitable means for maintaining it in various positions and the means employed is better shown in Fig. 6. By referring to this figure it will be seen that an arcuate apertured rack 15 is secured to the side board and that a spring pressed dog 16 is pivotally mounted on the aforesaid lever 14 and has its laterally directed end extending through an aperture in the latter so that it can be placed in any one of the 30 apertures in the rack to lock the lever in various positions.

It is to be noted that the aforesaid pockets 5 do not extend entirely to the ends of the trough and the endmost ones are spaced from the end pieces of the trough 35 to provide relatively large open spaces 17 and 18 through which excess water can escape. These large open spaces have chutes 17^a and 18^a beneath them, the first one being in the form of a board secured to the lower edges of the side pieces and having an inclined discharge plate 19 at its free end. The other chute is inclined from its point of connection with the narrow cross piece 3 at the lower end of the trough and terminates adjacent the lowermost pocket. It is 40 to be stated here that these chutes could be constructed otherwise and simply serve to convey excess water from the ends of the trough to a suitable point of discharge adjacent the center, and if desired suitable

conduits may be connected with the chutes to carry the waste water to distant points of discharge or the chutes may be brought rather close together to enable the water to be discharged at the center of the trough 70 into a suitable receptacle which may be placed beneath the latter.

In use, the coal or other material to be washed is deposited on the screen 4 as evenly as possible, or at the upper end of 75 the trough, and a supply of water is discharged onto the material so as to separate the waste dust and other small particles from the good coal, leaving only the large lumps on the screen to roll down the inclined surface of the latter and be discharged at the lower end of the trough into a pile or into a car, which ever is desired. As before pointed out, the excess water will pass along the chutes 17^a and 18^a and will be 80 discharged at the center of the trough and into a receptacle or will be taken care of in the manner above suggested. Of course, some of the waste material will be carried with this excess water, but the greater portion of the material will settle in the pockets 85 5 and in view of the fact that the latter adjoin one another, the water will flow from one to another and will assume a height to pass upwardly through the screen to loosen 90 the waste material which tends to stick on the latter and will carry such material downwardly and deposit it into one of the lower pockets or will carry it down so that it can be discharged with the water through the chute 95 18^a. When the pockets become filled with waste material, the operator simply grasps one of the handles 14 and depresses the upper end of the locking dog 15 to permit the handle to be moved in a direction where- 100 by a longitudinal movement will be imparted to the rod 8. As before pointed out, when this rod is so moved, it swings the movable sides 7 of the pockets to the positions shown in Figure 5 where the contents 105 is allowed to be dumped into a receiver. When the pockets are cleaned, the rod is moved to its original position again and the pockets closed. As above pointed out, there 110 will be operating means at either end of the trough to permit the rod 8 to be controlled from these points. The down flowing current of water passing through the trough, will, of course, carry the clean coal through the discharge end of the trough.

At this point, I wish to state that the trough and parts associated therewith may be made of wood or metal as preferred, and may be of any size and width to adapt the device to the working conditions and to the 115 proportion of discharge thrown onto the screen. The retractable sides of the pockets may be opened from time to time to control the flow of water to make the current slow or swift as desired and to permit a con- 120 125 130

tinuous discharge of the waste material. I am also led to state here that although I have confined the description more or less to using the device as a coal washer, I wish it 5 to be understood, as pointed out hereinbefore, that the device may well serve for washing other materials. Then again, the parts from which the pockets are formed may be composed of one stationary part and 10 one movable part or both parts may be made movable if such a pocket is found more desirable in practical use. Furthermore, the means for simultaneously operating the movable sides of the pockets need not be constructed exactly as shown and described, but 15 may be varied within the limits of the invention as claimed.

From the foregoing description it will be seen that by employing a trough embodying 20 the pockets having retractile sides, the water and materials to be washed can be deposited on the screen at one end or at any other suitable point and maintained in a uniform mass until thoroughly washed. It 25 will also be seen that with the structure shown, the foreign matter will be effectively separated and filtered through the screen into the pockets and carried to a suitable point of deposit, this being accomplished by 30 simply manipulating the operating levers at either end of the trough. Any suitable means may be employed for supporting the latter in various inclined positions.

Persons who read the foregoing description 35 carefully in connection with the accompanying drawings will doubtless be able to obtain a clear understanding of the invention. In view of this, a more lengthy and detailed description is thought un- 40 necessary.

Since probably the best results may be obtained with the construction and arrangement herein shown and described, this is taken as the preferred embodiment of the 45 invention. However, I wish it to be understood that minor changes coming within the

scope of the invention as claimed may be resorted to if desired.

I claim:

1. A device of the class described comprising a trough including a screen on which the material to be separated is deposited and a plurality of pockets arranged beneath said screen for collecting waste material, each pocket including one stationary inclined side and a substantially vertical retractile side, and means for actuating the last named sides of the pockets. 50 55

2. The structure set forth in claim 1, said actuating means for the retractile sides of the pocket, being a rod extending beneath 60 the pockets and having connection with the retractile sides for simultaneously actuating the latter, and means for moving said rod longitudinally. 65

3. A washing and separating device comprising a trough composed of longitudinal spaced side pieces connected together by transverse end pieces, a plurality of waste material collecting pockets arranged between said side pieces and spaced from said end pieces, each pocket being formed from an inclined part rigidly secured between the side pieces and a substantially vertical part hingedly connected with the upper end 70 of the adjacent stationary piece and bearing against the lower end of the adjoining stationary piece, a plurality of depending brackets secured to said hinged pieces, a longitudinally disposed rod pivotally connected with said brackets for simultaneously moving said hinged pieces, means for imparting longitudinal movement to said rod, a screen arranged between the side pieces of said trough and disposed over said 75 pocket and chutes arranged at the opposite ends of said trough for conveying waste materials to a suitable point of discharge. 80 85

In testimony whereof I have hereunto set my hand.

WILLIAM F. MARTIN.
